UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,402,073.

Specification of Letters Patent. Patented Jan. 3, 1922.

Application filed March 11, 1921. Serial No. 451,539.

To all whom it may concern:

Be it known that I, JOHN KIEWICZ, a citizen of the United States, residing at Boston, county of Suffolk, State of Massachusetts, have invented an Improvement in Button-hole-Sewing Machines, of which the following description, in connection with the accompanying drawing, is a specification, like characters on the drawing representing like parts.

This invention relates to buttonhole sewing machines, and particularly to the work-clamping device by which the work is held clamped while the stitching is being done on the buttonhole.

In order to stitch a buttonhole satisfactorily on a buttonhole sewing machine it is necessary that the work should be stretched slightly or held taut in a direction transversely of the buttonhole, and the object of the present invention is to provide a novel means for thus stretching the work slightly when it is clamped in position by the work clamps.

The work-holding means usually used in buttonhole sewing machines comprises a clamp plate on which the work is laid and two work clamps constructed to clamp the work against the clamp plate, the two work clamps being situated on either side of the buttonhole. In my present invention I propose to make the clamp plate with two grooves situated on opposite sides of the sewing opening through the clamp plate and also situated at a slightly greater distance apart than the work clamps when they are in their elevated position, and I propose to construct the work clamps so that when they are depressed to clamp the work they will enter the grooves and during this operation will be separated slightly thereby stretching the work.

My invention is capable of use in connection with buttonhole sewing machines of different types but I have herein chosen to illustrate it as it might be embodied in a sewing machine of the type illustrated in United States Patents No. 749,776, Jan. 19, 1904, and No. 1,088,652, Feb. 24, 1914. I desire to state, however, that the invention is not limited to its use in connection with buttonhole sewing machines such as illustrated in said patents but may be used equally well

in connection with other buttonhole sewing machines.

In the drawings, Fig. 1 is a side view of a buttonhole sewing machine of the type illustrated in the above-mentioned patents having my improvements applied thereto.

Fig. 2 is a plan view of the clamp plate and work clamps removed.

Fig. 3 is a bottom plan view of the clamp plate.

Fig. 4 is an enlarged section on substantially the line 4—4, Fig. 1 showing the work clamped.

Fig. 5 is a view similar to Fig. 4 showing the clamps raised.

The sewing machine herein illustrated comprises the bed frame 1 from which rises the overhanging arm 2 that supports the vertically reciprocating needle bar 3 carrying the needle 4. 5 indicates the buttonhole cutter which is carried by a lever 6 pivoted to turn about a rock shaft 7 carried by the frame. The work-holding means comprises the usual clamp plate 8 on which the work ⁷⁰ _w is placed, and which is provided with the slot or sewing opening 9 through which the needle operates, and the two work clamps 10 situated on opposite sides of the sewing opening and carried by arms 11 that are pivotally mounted to the clamp plate at 12.

In the sewing machine herein illustrated the arms 11 are carried by a rocker 13 which is pivoted to the rock shaft 12 and the rocker has a tail 14 extending rearwardly therefrom, said tail underlying a lever 15 pivoted to the frame at 16. This lever 15 is provided with a handle 17 so that by swinging the handle 17 to the left of Fig. 1 the lever 15 may be pressed against the tail 14 thereby to elevate the work clamps 10. The work clamps are also raised automatically at the end of the stitching operation on the button-hole by a mechanism similar to that described in the above-mentioned patents and which comprises a latch member 18 which is pivoted to the lever 15 and is adapted to be engaged by an arm 19 forming part of the controlling mechanism which controls the starting and stopping of the machine. When the buttonhole is completed and the stop mechanism comes into play to stop the machine the arm 19 at the same time engages the latch lever 18 and draws downwardly

thereon thereby causing the lever 15 to depress the tail 14 and elevate the work clamps all as shown in the above-mentioned patents. The work clamps are released at the beginning of the sewing operation by the lever 20 pivoted at 21 and carrying the depending portion 22 situated to engage the lower end of the latch when the lever 20 is depressed and thereby releasing the latch from the arm 19.

10 The work clamps are acted on by suitable springs which automatically move them down in work-clamping position when the latch lever 18 is released from the arm 19.

15 The parts thus far described are, or may be, all as shown in the above-mentioned patents and therefore a more detail description is not necessary.

20 In my present invention the two arms 11 carrying the work clamps 10 are pivotally mounted on the rocker 13 as shown at 23 so that the arms may swing about the pivots 23 toward and from each other. The springs which automatically depress the work clamps into work-clamping position are 25 shown at 24 and they are in the nature of coil springs encircling rods or pins 25 that rise from the arms 11. The upper ends of the springs abut against a bridge piece 26 through which the pins 25 loosely extend 30 and which is carried by a bracket 27 secured to the clamp plate 8.

35 The clamp plate 8 is provided with two grooves 28 situated on opposite sides of the sewing opening 9 and extending parallel thereto, each groove preferably having inclined side walls so as to present a V formation. The under face of each work clamp 10 has a similar V-shape to fit the groove 28, each under face comprising the 40 two inclined surfaces 29 and 30.

45 The work clamps are constructed so that when they are in their raised position, shown in Figs. 1 and 5, they will be slightly nearer together than the grooves 28 and as a result when the clamps are depressed to clamp the work the inner inclined faces 30 of the work clamps will first engage the inner walls of the grooves as shown in dotted lines Fig. 5, so that in entering the grooves 50 and assuming the work-clamping position shown in Fig. 4 the work clamps are spread or separated slightly. This spreading of the work clamps by their entering the grooves 28 operates to stretch the work and place it under the desired tension so that the buttonhole can be properly stitched therein.

55 When the work *w* is placed on the clamp plate with the work clamps raised it will 60 have the position shown in Fig. 5 and when the work clamps are depressed the inclined faces 30 thereof will engage the work at substantially the points 31 and when the work clamps have their final movement into the 65 position shown in Fig. 4 the engagement of

the faces 30 thereof with the work *w* will tend to stretch the work so that the portion thereof which spans the sewing opening 9 will be under tension. The stretching of the work, therefore, is accomplished partly by 70 forcing the work into the grooves 28 and partly by the spreading movement of the work clamps as they enter the grooves.

Means are also provided whereby when the work clamps are raised at the end of 75 each sewing operation they will be automatically moved toward each other back into the position shown in Fig. 5.

For this purpose the bridge portion 26 is provided with two arms 32 having cam faces 80 33 situated to engage the sides of the work clamp supporting arms 11 as said arms are raised. The action of these cam surfaces 33 against the arms 11 will force the arms inwardly into the position shown in Fig. 5. 85

It sometimes happens that during the stitching of a buttonhole the thread will skip thus making it necessary to sew the buttonhole over again. In this type of sewing machine the buttonhole cutter operates to 90 cut the buttonhole only after the buttonhole is sewed. If, however, it is necessary to sew the buttonhole over again, then such second sewing operation is performed on a cut buttonhole and when the work clamps are depressed and are carried into the grooves the 95 action of the work clamps on the fabric having a cut buttonhole therein is likely to stretch or open the buttonhole to such an extent that the stitches would not be properly formed. 100

I have provided therefore means by which the work clamps are prevented from being spread when the sewing machine is operating on a cut buttonhole. Such means 105 comprises a locking lever 34 pivoted to one of the clamp arms 11 at 35 and having a notch 36 adapted to engage a pin 37 carried by the other arm 11. So long as the lever 34 is disengaged from the pin 37 the arms 110 11 are free to be spread but if the lever 34 is swung into dotted line position Fig. 2 when the work clamps are raised thereby causing the pin 37 to enter the notch 36, then the arms 11 will be held from spreading 115 movement so that when the work clamp is depressed said arms will remain in the dotted line position Fig. 5 and will therefore exert no spreading or stretching action on the work *w*. This lever 34 can be readily 120 operated manually by the operator whenever it becomes necessary to stitch a buttonhole for a second time.

I claim.

1. In a buttonhole sewing machine, the 125 combination with a clamp plate having a sewing opening and provided with a groove on each side of said opening, of work-clamping arms, a rocking block to which the arms are pivoted so that the arms may swing to- 130

ward each other, the rocking movement of the block permitting the arms to move toward and from the clamp plate, each arm carrying at its end a work-clamping portion 5 shaped to fit the groove, the work-clamping portions of said arms normally being situated a less distance apart than the grooves, whereby when the work-clamping arms are moved into work-clamping position they engage 10 the sides of the grooves and are spread thereby to stretch the cloth.

2. In a buttonhole sewing machine, the combination with a clamp plate having a sewing opening and two V-shaped grooves on 15 opposite sides of said opening, of two work clamps pivotally mounted on said clamp plate for movement toward and from the latter and also mounted for movement toward and from each other, said work clamps 20 having clamping faces to fit the grooves and being normally situated at a less distance apart than the grooves, whereby when the work clamps are depressed into clamping position they engage the inner walls of the 25 grooves and are separated thereby stretching the work.

3. In a buttonhole sewing machine, the combination with a clamp plate having a sewing opening and two V shaped grooves 30 on opposite sides of said opening, of two work clamps mounted on said clamp plate for movement toward and from the latter and toward and from each other, said work clamps having clamping faces to fit the 35 grooves and being normally situated at a less distance apart than the grooves, whereby when the work clamps are depressed into clamping position they have a spreading action as they enter the grooves thereby to 40 stretch the work, and means to move said clamps positively toward each other when they are raised.

4. In a buttonhole sewing machine, the combination with a work plate, of two work- 45 clamping arms pivotally mounted thereon

to move toward and from the clamp plate and also toward and from each other, and means to spread the work-clamping arms by or through their work clamping movement and other means to move the arms positively 50 toward each other by or through their movement away from the clamp plate.

5. In a buttonhole sewing machine, the combination with a clamp plate having a 55 sewing opening and a groove on each side of the sewing opening, said grooves having inclined walls, of two work clamps pivotally mounted on the clamp plate and having inclined clamping faces, and means to move the work clamps toward the clamp plate, the 60 inclined faces of the work clamp and groove cooperating during such movement to spread the clamps thereby stretching the work.

6. In a buttonhole sewing machine, the combination with a clamp plate having a 65 sewing opening and a groove on each side of the sewing opening, said grooves having inclined walls, of two work clamps pivotally mounted on the clamp plate and having inclined clamping faces, means to move the 70 work clamps toward and from the clamp plate, the engagement of the inclined faces of the work clamps and grooves operating to spread the clamps during the work clamping movement thereby to stretch the work, 75 and means to move the clamps together during their movement away from the clamp plate.

7. In a buttonhole sewing machine, the combination with a clamp plate, of two 80 work clamps pivotally mounted thereon and capable of movement toward and from each other, means to cause a separating movement of the work clamps as they move into work clamping position, and means to lock 85 the work clamps from separating movement.

In testimony whereof, I have signed my name to this specification.

JOHN KIEWICZ.

Certificate of Correction.

It is hereby certified that in Letters Patent No. 1,402,073, granted January 3, 1922, upon the application of John Kiewicz, of Boston, Massachusetts, for an improvement in "Buttonhole-Sewing Machines," an error appears in the printed specification requiring correction as follows: Page 3, line 1, claim 1, before the word "each" insert the words *and from*; and that the said Letters Patent should be read with this correction therein that the same may conform to the record of the case in the Patent Office.

Signed and sealed this 14th day of February, A. D., 1922.

[SEAL.]

KARL FENNING,

Acting Commissioner of Patents.
